UNITED STATES PATENT OFFICE.

JOSEPH P. HOLMES, OF CASPER, WYOMING.

KEYLESS PADLOCK.

1,181,449.

Specification of Letters Patent.

Patented May 2, 1916.

Application filed April 25, 1914. Serial No. 834,484.

To all whom it may concern:

Be it known that I, JOSEPH P. HOLMES, a citizen of the United States, residing at Casper, in the county of Natrona and State of Wyoming, have invented certain new and useful Improvements in Keyless Padlocks, of which the following is a specification.

The object of my invention is to provide a keyless padlock of the permutation type, comprising few parts substantial in construction and all arranged in such a manner that the lock cannot be opened without the proper combination, and one which presents the parts in such a manner that they can be separated by violence only by the exertion of sufficient force to break the lock structure.

A further object is to provide a lock having a plurality of tumbler disks so constructed and arranged that each may be manually turned independently of the others to bring the disks to the combination at which the lock can be released.

With other objects in view, which will be referred to, my invention consists in the peculiar combination and novel arrangement of parts, such as will be hereinafter more fully described in connection with the accompanying drawing and more particularly pointed out in the appended claims.

In the drawing:—Figure 1 is a view in elevation of the lock with the cover plate removed to better illustrate the arrangement of the operating parts. Fig. 2 is a view in side elevation of the complete padlock. Fig. 3 is a view in transverse section through the body of the lock to illustrate the mounting of the tumbler disks. Fig. 4 is a view similar to Fig. 3 with the tumbler disks also in section.

The body 1 of the lock is cored out at 2 to form a case. A shackle 3 is pivoted by a pin 4 to the body portion and a shackle opening 5 is provided in the body 1 to receive the free end of the shackle 3. A bolt slot 6 is formed tangentially from the cored-out portion 2 and communicates with the shackle opening 5.

A cover plate 7 is provided to be received against the open side of the body 1 and is held in place thereon by rivets 8, 8. A lock bolt 9 is mounted to slide in the bolt slot 6 in such relation that its outer end extends through the slot into the shackle opening 5 and at the inner end this lock bolt has an arm 10. The shackle 3 on its free end has a

bolt notch 11 and when the bolt 9 is moved to its one extreme position the outer end thereof is received in this notch 11.

The cored-out portion 2 of the body 1 is made circular so that the case thus provided is circular, and an opening 13 of less diameter than the cored-out portion 2 is formed through the side of the body. A similar opening 12 is provided through the cover plate 7 and when this cover plate is in place on the body of the lock the two openings are in alinement. The tumbler disks 14, 15, 16 and 17 are mounted in the cored-out portions 2 and these disks have openings provided through their centers. The disks 14 and 17 which are the outer disks as mounted in the cored-out portion are made with their bodies of a sufficient radial width that faces 23 and 26 respectively are presented to be visible through the openings 13 and 12, and disks 15 and 16 are made of a slightly greater bodily width so that a portion of the face of the body thereof will be presented at 24 and 25 through the openings 7 of the disks 14 and 17.

The tumbler disks 14, 15, 16 and 17 have the radial slots 18, 19, 21, and 22, respectively, formed in their outer edges. The faces 23, 24, 25 and 26 of the disks which are visible through the openings 13 and 12, are marked off in dial figures as better shown in Figs. 1 and 2, thus making it possible to retain a record of the positioning of the slots 18, 19, 21, and 22, even after the lock has been assembled by placing the tumbler disks in the cored-out portion and then securing the cover plate 7 in place. It is the intention that these slots shall all be brought into registry when it is desired to open the lock and that the tumbler disks may be more readily turned in the cored-out portion the edges thereof adjacent the openings are milled or knurled to present a rough surface which may be gripped with the fingers.

The bolt slot 6 is made stepped as at 20 at its inner end, and when the bolt is in the position shown in Fig. 1 with the arm 10 thereof engaging with the periphery of one or several of the tumbler disks this bolt is held in a position that the outer end is engaged against displacement in the notch 11 of the shackle. When it is desired to withdraw the bolt from the notch in the free end of the shackle to release this shackle, the tumbler disks are turned to a relation that

the notches 18, 19, 21 and 22 are brought into registry, and then by rotating the several disks collectively to bring the registering notches beneath the arm 10 of the bolt 9, and exerting a pulling strain upon the free end of the shackle 3, the bolt 9 will be caused to be swung in a relation that the arm 10 thereof enters the notches. With the arm 10 of the bolt 9 in the notches, the tumbler disks are moved collectively in a turning path clockwise as the parts are illustrated in Fig. 1 and the bolt 9 as it is disengaged from the shoulder 20 of the slot 6 is then carried to the position indicated 15 by the dotted lines and the shackle is released. When the lock is to again be fastened, the free end of the shackle is closed into the shackle opening 5 and anti-clockwise movement is given to the tumbler disks 20 to cause the end of the bolt 9 to be engaged in the notch 11 of the shackle, then upon further inward movement of the free end of the shackle the bolt is swung to a position with the inner end thereof engaging the shoulder 20 of the slot 6 and the arm 10 is released from the notches of the tumbler disks 25 so that these disks may be independently turned to upset the releasing combination.

30 When it is desired to change the combination as indicated by the dials at which the bolt may be thrown, the disks 14, 15, 16 and 17 may be interchanged in their positioning within the body 1 of the lock, and to give 35 wide and varied scope to the combination of the lock as turned out at the factory the slots 18, 19, 21, and 22 may be stamped or cut at any point around the periphery of the tumbler disks and thus change the combination at which the slot of each disk comes 40 into registry with the slot of the remaining disk.

While I have herein shown and described one specific form of my invention, it will be understood that slight changes might be made in the form and arrangement of parts without departing from the spirit and scope of my invention, and hence I do not wish to be limited thereto except for such limitations as the claims may import.

I claim:

1. A lock of the type described comprising a case having an opening therethrough, a shackle, shackle holding means, a plurality of tumbler disks rotatably mounted within the casing to be accessible through said opening so that each can be moved manually to bring the disks to the proper combination at which the shackle holding means is released.

2. A lock of the type described comprising a case, a shackle mounted in the case, a plurality of tumbler disks rotatably mount-

ed in the case, a bolt mounted in the case adjacent the tumbler disks to engage with the shackle and hold said shackle in its closed or locked position, and the case provided with an opening therethrough through which access may be had to the disks and each disk may be moved manually to bring the several disks to the proper combination at which the bolt may be withdrawn from its engagement with the shackle.

3. In a lock of the type described, the case of which comprises a body portion and a cover plate each having an opening therethrough, a shackle mounted in the case, shackle holding means, and a plurality of tumbler disks mounted in the case to project within the opening so that each can be moved manually independently of the other disks to bring the several disks to the proper combination at which the shackle holding means is released.

4. In a lock of the type described, a case comprising a body portion and a cover plate provided with openings through the sides thereof to be in alinement, a shackle mounted in the case, shackle holding means, tumbler disks mounted in the case to extend within the openings thereof and provided with openings through their center of lesser diameter than the openings of the case, at least one tumbler disk mounted within the case between said outer disks to project within the opening therethrough, and all of the parts so arranged that each of the disks can be moved manually independently of the other disks to bring several disks to the proper combination at which the shackle holding means is released.

5. In a lock of the type described, a case comprising a body portion and a cover plate, a shackle mounted in the case, said body portion and cover plate provided with openings therethrough in alinement, a bolt positioned in the case adjacent the opening to engage with the end of the shackle and hold said shackle in its closed or locked position, a plurality of tumbler disks mounted in the case adjacent the openings therethrough and each provided with the usual tumbler slots, indicating dials on each of the tumbler disks to be visible through the opening of the case, and all of the parts so arranged that each of the disks may be moved manually to bring the several disks to the proper combination at which the bolt may be released from its locked position.

In testimony whereof I affix my signature in presence of two witnesses.

JOSEPH P. HOLMES.
